HULLER RIB

Jeffrey John Wallace, Amite, La., assignor to
Gullett Gin Company, Amite, La., a corpora-
tion of Louisiana

Application March 10, 1938, Serial No. 195,123

3 Claims. (Cl. 19—62)

This invention relates to certain new and useful improvements in huller ribs for use in cotton gins.

The main object of the invention is to provide huller ribs in cotton gins with cooperating upper working portions which automatically effect separation of the cotton with seed from the hulls and surplus cotton without possibility of wedging the cotton in the slots formed by adjacent huller ribs.

A further object of the invention is to provide cotton gins with huller ribs designed to eliminate such spaces between the gin saws and huller ribs as would prevent discharge of seed from the gin.

Other objects of the invention will become apparent as the detailed description thereof proceeds.

In the drawing:

Figure 1 is a fragmentary vertical cross-sectional view through a part of a huller rib cotton gin, showing the working elements of the gin associated with this improved type of huller rib;

Figure 2 is a fragmentary front elevation of several huller ribs assembled in accordance with this invention.

Figures 3, 4, 5, 6 and 7 are transverse sections taken on the lines 3—3, 4—4, 5—5, 6—6 and 7—7, respectively of Figure 1.

The form of the invention illustrated in the drawing comprises a double rib huller gin having a roll box 8, saw cylinder 9, ginning ribs 10, huller ribs 11, huller breast 12 and a spiked huller roller 13. With the exception of the huller ribs 11, all the parts described are of conventional construction.

Each huller rib 11, in accordance with general practice, has a lower end 14 adapted to be bolted to the bottom rib rail 15; and has its upper end 16 adapted to be bolted to the upper rib rail 17. These upper and lower ends of each huller rib constitute plates having parallel edges adapted to be bolted edge-to-edge with any desired number of similar plates on the aforesaid rib rails.

The huller ribs, between their securing ends, are reduced in width to form slots 18 through which the gin saws 19 project to separate the bolls and other extraneous matter from the cotton prior to the presentation of the cotton with seed to the ginning ribs 10. In the present invention, the lower ends 20 of the slots 18 are brought as close as possible to the saws to prevent accumulation of debris between the peripheries of the saws and the bottoms of the slots. The high speed saws act as scavengers to

keep these spaces clear of accumulated debris. This construction presents decided advantages over the conventional type huller rib assembly, and eliminates the possibility of small limbs or other matter becoming jammed to close up the seed discharge outlet between the hulling and ginning ribs.

The upper ends of the hulling ribs 11 between the flanges 16 and the points where the saws 9 re-enter the slots 20, are peculiarly shaped to prevent wedging of the cotton on either the huller breast or roll box sides of the ribs. From the lower plate-like ends 14 of the hulling ribs 11 to the reentrant points, each hulling rib has its working face 21 substantially perpendicular to a plane at right angles to the axis of the saw cylinder, and its opposite sides 22 and 23 parallel to said plane. This means that each hulling rib is substantially rectangular in cross section between those points where the saws enter 20 and leave the huller breast.

Beyond the line 24, on which the saw re-entrant points lie, each hulling rib extends in opposite directions, into the huller breast and roll box, from straight edges 25 and 26. The straight edges 25 and 26 lie in a plane which forms a continuation of the main working face 21 of the hulling rib, and are continuations of the edges 25' and 26' of said working faces 21.

From the straight edges 25 and 26, each hulling rib is bevelled in opposite directions to form clearances in the huller breast and in the roll box which increase both upwardly from the saws and in opposite directions from the straight edges as the ribs approach their flanges 16. This means that the cotton rising on opposite sides of the straight edges 25 and 26 will have increasing clearances in the roll box and in the huller breast, which will prevent wedging of the cotton in either of these compartments.

The plane of the straight edges 25 and 26 forms a plane of division for the separation of the hulls from the cotton and for the return stream of surplus cotton, since the ribs taper from this plane toward the front and the space between them gradually widens in the upward direction of the ribs. On the rear side of the aforesaid plane the tapering of the ribs increases gradually so that the cotton can be carried upwardly by the saws into the roll box without wedging of the cotton between the ribs.

While I have shown and described the invention as embodied in a particular form, it is not to be considered as limited to that form, nor in

any other manner except as indicated by the scope of the claims appended hereto.

What I claim is:

1. In a huller gin, a saw cylinder, a set of huller ribs disposed between the saws, said ribs being curved at their upper parts to extend into the huller breast and across the peripheries of the saws, each rib having straight edges on its opposite sides lying in a plane tangent to the curves at the points of intersection thereof with the peripheries of the saws, each of said parts being bevelled in opposite directions from said straight edges to provide gradually increasing clearances into the huller breast and roll box of the gin of the cotton moved by the saws into said upper parts.
2. A huller rib for cotton gins having its upper part curved to extend across the periphery of a gin saw into the huller breast of the gin, said part having substantially parallel straight edges

lying in a plane tangent to the curve at its point of intersection with the periphery of the saw, and being bevelled rearwardly to provide with corresponding parts of similar adjacent huller ribs gradually increasing clearances into the roll 5 box of the cotton moved by the saws into the spaces between straight edges of adjacent ribs.

3. A huller rib for cotton gins having its upper part curved to extend across the periphery of a gin saw into the huller breast of the gin, 10 said part having substantially parallel straight edges lying in a plane tangent to the curve at its point of intersection with the periphery of the saw, and being bevelled forwardly to provide with corresponding parts of similar adjacent huller 15 ribs gradually increasing clearances into the huller breast of the cotton moved by the saws into the spaces between straight edges of adjacent ribs.

JEFFREY JOHN WALLACE. 20
